[57] CLAIM

The ornamental design for a tub, as shown and described.

DESCRIPTION

FIG. 1 is a top, front, and right side perspective view of a tub showing my new design;

FIG. 2 is a top plan view thereof;

FIG. 3 is a left side elevational view, the right side being a mirror image thereof;

FIG. 4 is a front elevational view thereof;

FIG. 5 is a rear elevational view thereof; and,

FIG. 6 is a bottom plan view thereof.

The broken line showing is for illustrative purposes only and forms no part of the claimed design.
